UNITED STATES PATENT OFFICE.

ISAAC NIEMI, OF EBEN JUNCTION, MICHIGAN, ASSIGNOR OF ONE-HALF TO ANDREW SALMI, OF EBEN JUNCTION, MICHIGAN.

RAIL-TIE.

1,271,516.

Specification of Letters Patent.

Patented July 2, 1918.

Application filed November 25, 1916, Serial No. 133,364. Renewed December 29, 1917. Serial No. 209,601.

To all whom it may concern:

Be it known that I, ISAAC NIEMI, a citizen of Finland, Russia, residing at Eben Junction, in the county of Alger and State of 5 Michigan, have invented certain new and useful Improvements in Rail-Ties, of which the following is a specification.

This invention relates to improvements in rail ties and one object is to produce a rail 10 tie of durable construction. A further object is to produce a tie which will hold the ends of adjacent rails together without the use of fish plates. With the foregoing and other objects in view the invention consists 15 in the combination and arrangement of parts to be hereinafter fully described in this specification, pointed out in the appended claim and illustrated in the accompanying drawings which form a part of said 20 specification and in which—

Figure 1 is a top plan view of a portion of a railway right of way showing the application of my tie.

Fig. 2 is a side elevation of Fig. 1.

Fig. 3 is an enlarged fragmentary view 25 showing the manner of working a tie into engagement with the rail.

Fig. 4 is an end elevation, enlarged, showing how the rail ends are connected by my 30 tie.

Fig. 5 is a view of the tie in side elevation.

Fig. 6 is a section on line 6—6 of Fig. 5.

Fig. 7 is a similar view on line 7—7 of 35 Fig. 9.

Fig. 8 is a perspective view of a portion of the tie showing one of the openings formed therein.

Fig. 9 is a top plan view of Fig. 4.

Fig. 10 illustrates the form of blank used 40 to make one form of tie.

Like reference characters denote corresponding parts throughout the several views.

The tie consists of a hollow member 1, oblong 45 in cross section and formed adjacent each end with oblique openings 2, the openings in each tie being spaced away from each other a distance substantially equal to

the distance between the rails of a standard 50 railway track. The ties are made in what may be termed "rights" and "lefts," that is one tie is made with its openings 2 inclined to the right and the next tie with its openings 2 inclined toward the left. The right 55 and left ties are laid alternately. The opening 2 in each tie is formed by cutting through the top or tread of the tie obliquely as at 3 and 4 and the cut 3 continued straight down one side of the tie as at 5 and 60 curved or beveled away from the opening 2 through part of the other side of the tie as at 6; part of this cut being straight, however, as at 6^a. The cut 4 is continued with a combination straight and bevel cut, 65 7, 8 down one side of the tie opposite the straight cut 5, and with a straight cut 9 opposite the cut 6, 6^a. The opposite sides of the tie are cut an equal depth thus forming ledges 10, 11 which serve as supports for the 70 rail 12, the flanges of the rail projecting into the beveled cuts 6 and 8 of opening 2.

The ties laid beneath the meeting ends of rails are of somewhat different construction from the ties just described as they are 75 formed of a blank of the shape shown in Fig. 10. This blank is formed with lateral lugs 13 which in making the tie are bent upward (see Fig. 7) to meet tongues 14 which are pressed out of the sides and top 80 or tread of the tie. The tongues 14 and lugs 13 form a partition upon which the meeting ends of the rails 12 rest, the flanges of said rails being secured to said tongues 14 by bolts 15. A tie is placed beneath a rail in 85 the usual manner only the trough made in the earth to receive the tie is wider than is ordinarily used in order to permit lateral movement of the tie (see Fig. 3) to permit it to be worked into engagement with the rail. 90

When the ties are placed in position they are filled with cement, the cement being forced into the ties in plastic form and, when it hardens serving as an anchor and filler for the hollow tie bodies.

What is claimed is:—

In a railway tie, a hollow tie body formed with spaced openings extending obliquely

thereacross, said body comprising a base, lugs formed integral with said base, tongues formed integral with the body of the tie for coöperation with said lugs to form a rail-receiving partition, and a filler for said tie body.

In testimony that I claim the foregoing

as my own I have hereto affixed my signature in the presence of two subscribing witnesses.

ISAAC NIEMI.
